UNITED STATES PATENT OFFICE

CHARLES E. LABOURN, OF KANSAS CITY, MISSOURI.

OVERSHOE.

1,258,024.

Specification of Letters Patent. Patented Mar. 5, 1918.

Application filed October 23, 1916. Serial No. 127,244.

To all whom it may concern:

Be it known that I, CHARLES E. LABOURN, a citizen of the United States, residing at Kansas City, in the county of Jackson and State of Missouri, have invented certain new and useful Improvements in Overshoes, of which the following is a specification.

My invention relates to improvements in a new article of manufacture in the form 10 of an overshoe, and one object is to provide an overshoe made of one piece of strong, durable, and inexpensive fabric such as burlap, canvas, etc.

A further object is to produce an article of 15 this character which can be manufactured and sold for a small sum, in order to be within the reach of persons of limited means who will find the overshoe useful in protecting their leather shoes from wear and in keeping 20 their feet warm and comfortable in cold weather.

Other objects of the invention will hereinafter appear, and in order that said invention may be fully understood, reference will 25 now be made to the accompanying drawing, in which:

Figure 1 is a perspective view of a complete overshoe made in accordance with the invention.

Fig. 2 is a plan view of the blank from 30 which the overshoe is formed.

In carrying out the invention, I take a piece of burlap or other suitable fabric, and cut therefrom a blank 1 consisting of substantially parallel straight sides 2 and 3, substantially parallel ends 4 and 5, and curved edges 6, 7, 8 and 9, as disclosed by Fig. 2.

After the blank 1 has been properly formed as above described, it is folded along the 40 central transverse dotted lines 11 to bring the oppositely-disposed ends 4 and 5 together, so that the completed overshoe will have two thicknesses of fabric throughout to materially prolong the wearing quality 45 thereof. The folded blank is then sewed together at the sides 2 and 3, and the registering edges 6 and 7 and 8 and 9, respectively, are sewed together from their juncture with the sides 2 and 3, about half way 50 to their juncture with the ends 4 and 5. The article is then turned inside out and temporarily folded along the line 15 to bring the folded edges 3 and 2 together and the edges 6, 7, 8 and 9, in register with each other. 55 Said registering edges 6, 7, 8 and 9 are then

sewed together from their juncture with the ends 4 and 5 to a point about midway to their juncture with the sides 2 and 3. This leaves an opening 16 in the front and top of the overshoe, so that the same can be readily slipped on and off by the wearer. The back seam 17, running along the lines 11, is next sewed to close the back of the overshoe and stitching is run along the curved lines 12 to give the heel 13 a rounded appearance. 60 The temporary fold along the line 15 is next flattened out and creases along the lines 20 are formed to make the lower portion of the overshoe conform more to the shape of an ordinary leather shoe, after which the various thicknesses at the toe are sewed together to close the same and stitching is run around the curved lines 22 to round off the corners of the toe. 65

The overshoe is then turned right side 70 out to turn the rough edges inward and give the overshoe a finished appearance.

Suitable eyelets 19, are formed along the edges of the opening 16 to receive a suitable lace for securing the overshoe upon the foot. 80

From the foregoing description, it is apparent that I have produced an overshoe possessing the features of advantage above enumerated, and while I have shown and described the preferred form of the shoe, I 85 reserve the right to make such changes in the construction, proportion, and arrangement of parts as properly fall within the spirit and scope of the claim.

Having thus described my invention, what 90 I claim and desire to secure by Letters Patent, is:

As a new article of manufacture, an overshoe made from a single blank having parallel side and end edges connected by curved 95 edges, said blank being folded along a transverse median line to bring said end edges into register and to bring the curved edges on one side of said median line into register with the curved edges on the other side of 100 said line, the blank being again folded and stitched together in such manner as to form a complete shoe having a sole and upper of double thickness of material throughout.

In testimony whereof I affix my signature, 105 in the presence of two witnesses.

CHARLES E. LABOURN.
